UNITED STATES PATENT OFFICE.

HARRY R. KIESSIG, OF SAN DIEGO, CALIFORNIA.

POPPET-VALVE SELF-CORRECTING MEANS.

Application filed December 14, 1926. Serial No. 154,702.

My invention relates to poppet-valves, and more particularly to means whereby such valves may be rotatively adjusted, from time to time, in order to effect the 5 correction of the seating faces by preventing the localization of wear or deterioration.

The principal object of my invention is to provide such a device of simple form, and to combine it with the usual means for retaining the spring abutment upon the valve stem, in order to avoid multiplicity of parts. A further object is to provide such a device which may be readily adapted to any of the forms of spring retaining keys in common 15 use. A still further object is to provide means for conveniently grasping the device, either by the hand or with a suitable tool, when it is desired to turn the valve to a new position, and to provide suitable marks or 20 indicia upon the device so that the valve may be turned to the desired position.

Other objects and advantages of the invention will be apparent from the following description, which should be read with the 25 understanding that changes, within the scope of the appended claims, may be made in the form, construction and arrangement of the several parts, without departing from the spirit of the invention as set forth in 30 said claims.

With this in view my invention will now be described fully with reference to the accompanying drawings, wherein:—

Fig. 1 is a plan or end view, partly in section, of a preferred form of my device as applied to a well known form of retaining key which extends through a slot in the valve stem, and illustrating, in dotted lines, a convenient form of tool for turning the 35 valve by engagement with my improved dial or turning member. This view is taken on the line 1—1 of Fig. 2.

Fig. 2 is a section on the line 2—2 of Fig. 1.

Fig. 3 is a plan view of my preferred form of dial or turning member, showing the method of forming the key-engaging lugs.

Fig. 4 is a section on the line 4—4 of Fig. 50 3, showing the lugs after they have been formed.

Fig. 5 is a plan or end view, partly in section, of my preferred form of dial or turning member as adapted for the reception 55 of a well known form of U-shaped retaining key.

Fig. 6 is a section on the line 6—6 of Fig. 5.

Fig. 7 is a plan or end view, partly in section, of my preferred form of dial or turning member as adapted for the reception of a well known form of split cone key, and is taken on the line 7—7 of Fig. 8.

Fig. 8 is a section on the line 8—8 of Fig. 7.

Fig. 9 is a side elevation, enlarged, of one half of a slightly different form of split-cone key, and is taken on the line 9—9 of Fig. 10, the valve stem being omitted for the sake of clearness.

Fig. 10 is a transverse section showing the inter-fitting relation between the form of key shown in Fig. 9 and the valve stem, and is taken on the plane of the line 10—10 of Fig. 9.

Fig. 11 is an elevation of a portion of the valve stem shown in Fig. 10.

Fig. 12 is a part-sectional perspective view of a modified form of dial or turning member as adapted for the reception of a straight key extending through a slot in the valve stem.

In the drawings, and referring for the moment to Figs. 1 and 2 thereof, the reference numeral 1 designates a poppet valve having a stem 2. A portion of the usual spring for closing the valve is shown at 3. 4 is an abutment or washer against which the spring bears. 5 is a member which is removably secured upon the end portion of the valve stem for retaining the washer 4 and the spring 3 in place. If desired, an anti-friction bearing washer 6 may be interposed between the spring abutment 4 and the member 5, for a purpose to be described hereinafter.

The valve stem 2 is provided with a transverse key way 7 extending through it and adapted for the reception of a key 8 in the usual manner. The member 5 is provided with a depression 9 in its outer face, within which the key 8 lies. Thus the key retains the member 5 upon the stem, and said member, by its depression 9, retains the key in position. The placing and removal of the key is accomplished, as usual, by moving the member 5 along the stem toward the head of the valve, against the compression of the spring, to enable its outer rim to clear the key way 7.

The member 5 is not only retained upon the stem 2 endwise by the key 8, but is also

prevented from turning thereon by said key, so that the valve may be turned by turning said member 5. For this purpose the member 5 is provided with raised lugs 10 suitably spaced to enable the key to lie between them, as shown.

I prefer to make the turning member 5 from a flat piece of metal, the first step being the pressing of it into cupped shape to provide the depression 9, and the punching of a central hole 11, as shown in Fig. 3. This central hole is irregular, as shown, with tongues 12 projecting into it. Then by means of suitable dies, not shown, said tongues 12 are bent upwardly to form the lugs 10, as shown in Fig. 4. In this operation, the lugs 10 are sheared out and bent as indicated by the dotted lines in Fig. 3. By this method the member 5 is formed very cheaply.

The rim of the member 5 is preferably formed with notches 13, to enable it to be easily grasped, either by hand or with a suitable tool. As one form of such a tool, I have shown, in dotted lines in Figs. 1 and 2, a pair of pliers 14, whose jaws are formed with flat guide portions 15 adapted to lie against the outer face of the member 5, and with downwardly projecting lugs 16 to engage the notches 13 of said member. The bottoms of said notches are preferably formed with an undercut slope, as shown, and the lugs 16 of the tool are similarly sloped, so that, when said tool is in position, it cannot slip off the member 5 without being released, the sloping notches 13 and lugs 16 preventing it from slipping off upwardly, and the flat guide portions 15 preventing it from slipping downwardly. The tool may, therefore, be used even while the valve is in operation.

The rim portion of the member 5 is preferably provided with suitable marks or indicia 17, which may be in the form of numerals, as shown. In order that these indicia may be as large as possible, to be more easily seen, they are preferably placed between the notches 13. It is also preferable, for reasons to be set forth later, to space the indicia by progressively increasing distances, and in order to permit such spacing, the notches 13 are best located in pairs in the manner shown. By this means the notches are symmetrically positioned, to facilitate engagement by a grasping tool as described above, and still do not limit the size of the indicia nor interfere with the progressively increasing spacing thereof.

The use of the device, assuming it to be applied to the valves of an automobile engine, for example, is as follows. When the valves are newly ground, they are all set with the numerals 4 opposite some fixed part of the engine. Then after the engine has run for a certain time, corresponding, say,

to 300 miles running of the automobile, the valves are turned, by hand or by a suitable tool as described, to bring the numerals 1 to the former position of the numerals 4. This brings different portions of the valve 70 face and seat into contact, and the natural percussive action of the valve upon its seat, in the new position, beats out and corrects any impairment of the valve face or seat which may have been sustained during the 75 previous setting on position. After another period of running, the valves are again turned to the next numeral, and so on. It is desirable to turn the valve back and forth a few times before making each setting, to 80 loosen carbon.

It is necessary to turn the valves through different arcuate distances each time they are adjusted, to prevent the re-engagement of correlative points. Thus if the successive 85 positions or settings are spaced, say, by 50, 80, 105, and 125 degrees, then beginning over again with 50 degrees, the meeting faces of the valves and their seats will be always brought to new positions at each setting, no 90 matter how many re-settings may be made, and the faces and seats of the valves, as well as their stems and guides, will be kept in good condition indefinitely. It is for this reason that I prefer to space the indicia on 95 the member 5 by progressively increasing distances, so the optimum settings can be determined instantly.

My device is also of use when it is desired to turn the valve for any other purpose, as 100 for example to dislodge carbon from the seating faces by the "tap and turn" method, preferably with the use of a lubricant such as kerosene.

It will readily be understood that the use 105 of the member 5 to turn the valve is made possible by its non-rotatable connection therewith, such connections, in the form of the device described above, being formed by the lugs 13 which engage the key 8. By providing a separate abutment 4 for the spring 3 and a suitable anti-friction washer 6, as described, the friction and resistance to turning is reduced to a point consistent with proper and convenient operation. It should 115 be noted, in this connection, that the key is housed within the depression of the member 5, and is retained in position by the side wall of said depression. The advantages of such construction, which are well known in the 120 art, are thus retained.

In Figs. 5 and 6 I have shown my turning member designated 5^a, as adapted for the reception of a U-shaped key. The lugs 10^a, instead of being bent upwardly from the 125 bottom of the turning member as before, are bent inwardly from the sides of its depression 9^a, and engage notches 18^a in the sides of the key 8^a. The key itself is provided with a slot 19^a, the sides of which engage 130

opposite straight-bottomed grooves 7^a in the valve stem 2^a. As a further precaution against turning upon said stem, the key is provided with a tongue 20^a, Fig. 5, engaging a corresponding notch in the valve stem.

5 In Figs. 7 and 8 I have shown my turning member, designated 5^b, as adapted for the reception of a split-cone key. As in the form shown in Figs. 5 and 6, the key engaging lugs 10^b are bent inwardly from the sides of the depression 9^b, and engage notches 18^b in the outer edges of the key members 8^b. The depression 9^b is conical, and into it are fitted the two halves 8^b of the split-cone key, which also fit into straight-bottomed grooves 7^b in the valve stem 2^b.

Figs. 9, 10 and 11 illustrate a somewhat more effective means for preventing a split-cone key from turning upon the valve stem. 10 In this form the stem 2^c is provided with a circumferential groove 7^c, Fig. 11, which has oppositely spaced notches 20^c extending downwardly from it, said notches being separated by lands 21^c (Figs. 10 and 11). 15 The halves 8^c of the key are provided with corresponding notches 22^c and lands 23^c (Figs. 9 and 10). This construction provides a continuous shoulder 24^c (Fig. 11) to resist the thrust of the valve spring, and at 20 the same time provides substantial radial shoulders 25^c (Fig. 10) to resist turning. The key 8^c is adapted for reception in the same turning member as that shown at 5^b in Figs. 7 and 8.

35 In Fig. 12 I have shown a form of my device in which the key 8^d is provided with prongs or extensions 26^d upon its ends, which fit into notches 27^d in the turning member 5^d, the sides of said notches forming abutments 10^d having the same function as the lugs 10 of Figs. 1 and 2. The valve stem 2 is the same as that of Figs. 1 and 2, having a 40 transverse slot 7 through which the key 8^d passes.

45 Fig. 12 also illustrates a regular spacing of the notches 13^d in the rim of the turning member, and a similar regular spacing of the indicia 17^d.

It is to be noted that, in all forms of the 50 device, the turning member is formed with a depression in which the key is seated and by which said key is retained in position, and that means are provided for preventing relative rotation between said member and the valve stem. The turning member thus 55 performs two functions; it serves as an abutment and as a housing and retainer for the key, and as a member by which the valve may be turned. The turning member may 60 be provided with a dial as described and shown to make possible systematic re-positioning of the valve.

I claim:—

1. In combination with a poppet valve 65 having a stem and a spring surrounding said

stem, a member mounted upon said stem and having a depression in its face, said member receiving the end thrust of said spring; and means seated within and held in position by said depression for separably retaining said member upon said stem, said means having non-rotative engagement with the valve stem and with said member.

2. In combination with a poppet valve 75 having a stem and a spring surrounding said stem, a member mounted upon said stem and having a depression in its face, said member receiving the end thrust of said spring; and a key seated within and held in position by said depression, said key having non-rotative engagement with the valve stem and with 80 said member for retaining said member upon said stem.

3. In combination with a poppet valve 85 having a stem and a spring surrounding said stem, a member mounted upon said stem and having a depression in its face, said member receiving the end thrust of said spring; a key non-rotatably associated with said valve stem, said key being seated in and held in position by said depression; and an 90 abutment formed in the wall of said depression for engaging said key to hold said member in non-rotative relation upon said stem.

4. In combination with a poppet valve 95 having a stem and a spring surrounding said stem, a member mounted upon said stem for receiving the end thrust of said spring, said member having a central depression and a 100 rim formed with peripheral grasping notches; and means seated within and held in position by said depression for separably retaining said member upon said stem; said means having non-rotative engagement with the valve stem and with said member.

5. In combination with a poppet valve 105 having a stem and a spring surrounding said stem, a member mounted upon said stem for receiving the end thrust of said spring, said member having a central depression and a 110 rim formed with peripheral grasping notches; said notches being disposed in pairs symmetrically about the periphery of said rim; visible indicia upon said rim, said indicia being disposed between said notches and separated by progressively increasing distances; and means seated within and held in position by the depression of said member 115 for retaining it in non-rotative relation upon said stem.

6. In combination with a poppet valve 120 having a stem and a spring surrounding said stem, a member mounted upon said stem for receiving the end thrust of said spring, said member having a central depression and a 125 surrounding rim; visible indicia upon said rim; and means seated within and held in position by said depression for separably retaining said member upon said stem, said 130

means having non-rotative engagement with the valve stem and with said member.

7. In combination with a poppet valve having a stem and a spring surrounding said stem, a member mounted upon said stem and having a depression in its face, said member receiving the end thrust of said spring; a key non-rotatably associated with said valve stem, said key being seated in and held in position by said depression; and a lug extending into said depression from its wall and adapted to engage said key to hold said member in non-rotative relation upon said stem.

8. In combination with a poppet valve 15 having a stem and a spring surrounding said stem, a member mounted upon said stem for receiving the end thrust of said spring; a key associated in non-rotative relation with said stem for separably retaining said 20 member thereupon; and a lug adapted to engage said key, said lug being formed by partially cutting out a portion of said member and bending said portion upwardly.

In testimony whereof I have signed my 25 name to this specification.

HARRY R. KIESSIG.
